INVENTOR:
FRANK ETTINGER,
Br: Ollie H. Kueger,
his Atty.

UNITED STATES PATENT OFFICE.

FRANK ETTINGER, OF LOS ANGELES, CALIFORNIA.

WRENCH ATTACHMENT.

1,396,171.

Specification of Letters Patent.

Patented Nov. 8, 1921.

Application filed March 30, 1921. Serial No. 456,955.

To all whom it may concern:

Be it known that I, FRANK ETTINGER, a citizen of the United States, residing at Los Angeles, in the county of Los Angeles and State of California, have invented a new and useful Wrench Attachment, of which the following is a specification.

This invention relates to devices for adjustably grasping and holding articles like nuts, bolts and screws.

One of the objects of this invention is to provide means for locking a device in certain desired and indicated positions so that such a wrench may be securely kept for repeated use in the same condition.

Another object is to facilitate a quick and efficient use of such a wrench at ascertained desired jaw-openings.

Another object is to provide indicating means and locking means in proper relation for assuring certain desired jaw openings.

Other objects will appear from the following description and appended claims as well as from the accompanying drawing, in which—

Figure 1 is a side elevation of a wrench to which my invention is applied.

Fig. 2 is a cross section on line 2—2 of Fig. 1.

Adjustable wrenches are made of various types, and the disclosures of this invention may easily be applied in various forms to different kinds of wrenches, most suitable, however, is the so-called monkey-wrench, illustrated in the drawing.

The jaw member 3 is normally provided rigidly on the stem 4. The jaw member 5 is normally provided with a sleeve-like portion 6 to slidably engage with the stem 4. The set screw 7 is provided with a nut-like or enlarged portion 8 for handling and operating the screw. The one end face 9 of the portion 8 is made to rest against the lug 10, while the opposite end face 11 limits the movement of the screw in that direction by engaging within the cut-out 12 of the stem 4.

The threaded portion of the screw 7 is made to engage with the portion 13 of the jaw member 5. A short smooth end 14 on the opposite end of the screw engages within the socket 15 in the lug 10. The double-faced or shouldered portion 8 of the screw 7 forms the thumb piece or knob or handle of the screw for turning the screw. The member 8 must therefore be suitably larger

than the adjacent members or parts of the wrench to be easily grasped by the operator. This, however, gives the disadvantage that the screw adjusts itself easily by being placed down on the floor or the working bench, since a moving of the wrench when so placed out of the hands of the user tends to roll or turn the large member 8 and thereby turning the screw and adjusting the wrench to disadvantage.

To overcome this common trouble in wrenches, locking and indicating means are provided to assure a desired setting and holding of the wrench.

The thumb piece 8 is provided with notches 16, more clearly illustrated in Fig. 2, to be engaged by the pawl 17. The pawl 17 is swingably engaged to the wrench by the pin, screw, or rivet 18, so that the pawl can swing to disengaging position, indicated at 19 in Fig. 1. A spring washer 20 is preferably inserted between the head of the pin 18 and the pawl 17, forming suitable friction means for the movements of the pawl so as to make the pawl stay in certain set positions. From the illustration in Fig. 2, the notches 16 in the thumb piece 8 are preferably formed to squarely engage with the front end of the pawl as indicated at 21 for locking the screw in one direction and also squarely engaging with the side of the pawl as indicated at 22 for locking the screw in the opposite turning direction. Such an arrangement tends to securely lock the screw 7 against a turning movement.

The indicating marks 23 on the stem 4 are arranged to serve for setting the wrench in certain desired positions to be so locked by the locking means so as to prevent an undesired adjusting while the wrench is being used. Many times, a wrench is being used close to and on a surface, and the thumb piece is subjected to a friction on the surface while a nut or bolt is tightened, thereby eventually causing an undesired adjustment of the wrench, which is prevented by the arrangement herewith disclosed. A wrench is also used in places where an adjustment is sometimes impossible. With this device, the wrench can be set according to the indicating marks and then locked to be used in this set and locked condition. The device is furthermore useful as a gage for measuring nuts and bolts when no other tool suitable for this is on hand.

Having thus described my invention, I claim:

1. In a wrench having a movable jaw, in combination with the adjusting screw of such a movable jaw, a locking member pivotally engaged with the wrench to swing in a plane parallel to the longitudinal axis of the device having means to prevent a turning of the said adjusting screw and having other means for holding the locking member in desired positions.
2. In a wrench, a stationary jaw, a movable jaw, and adjusting screw having a thumb portion for setting the movable jaw in desired relation to the stationary jaw, the

thumb portion having notches in its periphery longitudinally to the screw, a locking member pivotally provided on the stationary jaw at a point to be engaged with the notches in the thumb portion of the screw, the locking member being disposed on the stationary jaw to swing in a plane parallel to the longitudinal axis of the device.

In testimony that I claim the foregoing as my invention I have signed my name in 25 the presence of two subscribing witnesses.

FRANK ETTINGER.
